UNITED STATES PATENT OFFICE.

JOHN T. BINKLEY, OF CHICAGO, ILLINOIS.

LOCKING MECHANISM FOR BOXES, CASES, OR TRUNKS.

1,132,824.

Specification of Letters Patent. Patented Mar. 23, 1915.

Application filed June 10, 1914. Serial No. 844,160.

To all whom it may concern:

Be it known that I, JOHN T. BINKLEY, a citizen of the United States, residing at Chicago, in the county of Cook and State of Illinois, have invented a new and useful Improvement in Locking Mechanism for Boxes, Cases, or Trunks, of which the following is a specification.

My invention relates to improvements in locking mechanism, and more particularly to locking mechanism for suit cases and the like containers, though it will be readily understood from the following description that it may be used in many other situations, it being my desire to protect my invention regardless of the particular connection in which it is used.

My primary object is to provide improved locking means for the purpose stated which may be readily and conveniently operated and which will serve to securely lock the cover of the container equipped with the locking means.

Referring to the accompanying drawings—Figure 1 is a plan view of a dress-suit case to which my invention is applied. Fig. 2 is a section taken at the line 2 on Fig. 3 and viewed in the direction of the arrow, this view being on a reduced scale. Fig. 3 is a section taken at the line 3 on Fig. 2 and viewed in the direction of the arrow. Fig. 4 is a section taken at the line 4 on Fig. 2 and viewed in the direction of the arrow. Fig. 5 is a view in elevation of the key of the particular locking mechanism shown. Fig. 6 is a view of the interior of the lock showing the casing in section, this view showing the position assumed by the parts of the lock, when in unlocked position. Fig. 7 is a view like Fig. 6, showing the position assumed by the parts of the lock when the latter is in locked position; and Fig. 8, an enlarged section taken at the line 8 on Fig. 6 and viewed in the direction of the arrow.

I have chosen to illustrate my invention as applied to a suit case, the body-portion of which is represented at 9 and the cover-section at 10, my improved locking means being employed for releasably locking the cover in closed position on the body 9. Secured to the inner surface of the forwardly-extending flange 11 of the cover 10, as by

rivets 12, is a plate 13, the lower edge of which extends slightly below the edge of the flange 11 and is rearwardly bent to provide a shouldered-ledge 14. Coöperating with this shouldered ledge is a catch device carried by the body-portion 9 of the case, this catch in the construction illustrated comprising plates 15 and 16, the plates 15 being secured to the inner surface of the body 9 of the case, as by rivets 18, and the plate 16, which extends upwardly, being hingedly connected therewith, as by a piano-hinge 17. The plate 16 at its upper end carries a forwardly-extending flange 22 having an upwardly and rearwardly-deflected section 23, this plate at its flanged portion 22 being adapted to interlock with the shouldered portion 14 of the plate 13, and being normally drawn to such interlocking position by springs 24 rigidly secured at their lower ends to the body of the case and extending through slots 25 in the flange 22.

It will be understood from the foregoing description that, assuming the lid 11 to be raised, the swinging of the latter to closed position (Figs. 1, 3 and 4), will cause the plate 16 at its flange 22 to interlock with the shouldered portion 14 of the plate 13 (Figs. 3 and 4), the inclined flange 23 riding against the inclined under surface 26 provided on the plate 13, and thus the cover 11 will be held in closed position until the plate 16 is swung rearwardly on the hinge 17, and in opposition to the springs 24, to a position in which the flange 22 will be moved out of interlocking position relative to the shoulder 14.

The actuation of the plate 16 for disengaging the flange 22 from the shoulder 14 to release the cover 11, is effected by means of a push-button 27 which is rotatably mounted in an opening 28 in a ring 29 secured in the front plate 30 of a casing 31 and in an opening 32 in the rear wall of this casing, a flange 33 upon the button 27 preventing the withdrawal of the latter from the casing 31. The inner end of the button 27 extends closely adjacent to the plate 16 and is connected therewith by a screw 27^a passing through an opening 16^a in the plate 16 and thus when the button 27 is pushed inwardly, it will swing the plate 16 to the right in Fig. 3, thus disengaging the shoul-

ders 14 and 22, permitting the cover 11 to be swung away from the body-portion 9. The button 27 forms a part of the lock mechanism contained in the casing 31, for releasably locking this button, which forms the barrel of the lock, against inward movement, or, in other words, to prevent the plate 16 from being actuated.

Any suitable means for locking the button 27 against inward movement may be provided, those illustrated, and which I find to be desirable for my purpose, comprising tumblers 34 in the casing 31, pivoted on a pin 35 and adapted to be projected at their ends 36 into interlocking engagement with the shoulder 33 on the button 27 as represented in Fig. 7. These tumblers are provided at their ends 36 with shoulders 37 at which they are adapted to interlock with the shouldered portion 38 of a catch 39 journaled on a pin 40, the catch 39 being provided with a finger 41 between which and the shouldered ends of the tumbler 34, a double-ended spring 42, carried by a post 43, is interposed tending to rotate the tumblers 34 on their pivots in an anti-clockwise direction. The finger 34 bears, under the action of the spring 42 against a button 44 slidably confined at a restricted portion 45 thereof in a slot 46 in the plate 30. The barrel 27 contains a key-way 47 for receiving a key so formed, as to engage with the shouldered portions of the tumblers 34 and swing them out of interlocking engagement 35 with the flange 33, as shown in Fig. 7, in which movement these tumblers ride against the shouldered end 38 of the catch 39, lifting the latter against the action of the spring 42 and finally interlocking therewith, 40 as illustrated in Fig. 7 in which position the slide-button 44 occupies the position in the slot 46 as represented in Fig. 8.

When the tumblers 34 are in the position last referred to, the button 27 is free to be 45 pushed inwardly for swinging the plate 16, against the action of the springs 24, out of interlocking engagement at its shoulder 22 with the shoulder 14, assuming that the cover of the case is closed, as represented in 50 Figs. 1 to 4, inclusive, thereby unlocking the cover and permitting it to be raised.

Assuming that the cover is closed, when it is desired that it be locked against raising, the operator merely slides the button 44 to the left in Fig. 6, which thus rocks the shoulder 38 of the latch 39 upwardly, clearing the shoulders 37 on the tumblers 34, which thus permits the spring 42 to force the tumblers at their shouldered ends 36 into 60 interlocking position relative to the flange 33 on the button 27 (Fig. 7), which prevents the button 27 from being pressed inwardly until the proper key has been inserted into a key-way 47 in the button 27 and the key 65 turned to force the tumblers 34 into the posi-

tion of interlocking with the catch 39, such a key being represented at 48 and operating at its lug 49 thereon to ride against the tumblers 34 and force them to the position illustrated in Fig. 6.

While I have illustrated and described a particular form of my improved mechanism, I do not wish to be understood as intending to limit my invention thereto as the same may be variously modified and altered without departing from the spirit of my invention, it being my intention to claim my invention as broadly and as fully as the prior state of the art will permit.

What I claim as new and desire to secure by Letters Patent is—

1. The combination with a container formed of sections adapted to be closed together, of a push-button on one of said sections, a catch on the other of said sections, a member pivotally supported on said first-referred to section and movable in the direction of movement of, and by, said push-button, and provided with means for interlocking with said catch, and spring means for normally yieldingly holding said pivoted member in position for interlocking with said catch upon the act of closing said sections together.

2. The combination with a container formed of sections adapted to be closed together, of a push-button on one of said sections, an inwardly extending member on the other of said sections extending substantially the full length of the latter and forming a catch-surface, and a member supported on said first-referred-to section and movable in the direction of movement of, and by, said push-button, and provided with a forwardly projecting portion extending substantially the full length of said first-referred-to section and adapted to interlock with said first-named member.

3. The combination with a container formed of sections adapted to be closed together, of a push-button on one of said sections, a catch on the other of said sections, a member pivotally supported on said first-referred-to section and movable in the direction of movement of, and by, said push-button, and provided with means for interlocking with said catch, means for releasably locking said push-button against inward movement, and spring means for normally yieldingly holding said pivoted member in position for interlocking with said catch upon the act of closing said sections together.

4. The combination with a container formed of sections adapted to be closed together, of a push-button on one of said sections, an inwardly extending member on the other of said sections extending substantially the full length of the latter and forming a catch surface, a member supported on

said first-referred to section and movable in the direction of movement of, and by, said push-button, and provided with a forwardly projecting portion extending substantially the full length of said first-referred to section and adapted to interlock with said first-named member, and means for releasably holding said push-button against inward movement.

JOHN T. BINKLEY.
